UNITED STATES PATENT OFFICE.

WILLIAM E. BALL, OF ZANESVILLE, OHIO, ASSIGNOR TO WILLIAM H. ADAMS,
OF MUSKINGUM COUNTY, OHIO.

DESIGN FOR A NUT-LOCK WASHER.

SPECIFICATION forming part of Design No. 33,050, dated August 7, 1900.

Application filed July 5, 1900. Serial No. 22,635. Term of patent 14 years.

all whom it may concern:

Be it known that I, WILLIAM E. BALL, a citizen of the United States, residing at Zanesville, in the county of Muskingum and State of Ohio, have invented and produced a certain new and useful Design for a Nut-Lock Washer; and I do declare the following to be a full, clear, and exact description of the invention, such as will enable others skilled in the art to which it appertains to make and use the same, reference being had to the accompanying drawing, which forms a part of this specification.

This invention relates to new and useful designs for nut-lock washers, of which the following is a specification, reference being had to the accompanying drawing, forming part thereof.

The design of my washer is clearly illus-

trated in the accompanying drawing, in which 20 I have shown a plan view of the washer.

The design for my nut-lock washer comprises a triangular-shaped plate having on each straight edge thereof two semicircular scallops and a central circular-outlined aperture. The scallops on the straight edges are spaced apart, as shown in the drawing. 25

Having thus described my invention, what I claim to be new is—

The design for a nut-lock washer, substantially as shown and described. 30

In testimony whereof I affix my signature in presence of two witnesses.

WILLIAM E. BALL.
